UNITED STATES PATENT OFFICE.

HARVEY M. GILLESPIE, OF CHICAGO, ILLINOIS, ASSIGNOR TO THE P & M COMPANY, OF CHICAGO, ILLINOIS, A CORPORATION OF ILLINOIS.

RAIL ANCHOR.

Application filed November 12, 1925. Serial No. 63,590.

My invention relates to rail anchors of the general type adapted to engage the base flanges of a rail at opposite sides of the rail.

The principal object of the invention is 5 to provide an improved anchor of the above general type, which may be driven into firm wedging engagement with one flange of the rail base, and which is provided with a jaw portion so formed as to provide a resilient 10 gripping engagement with the other flange of the rail base, so as to hold the device against reverse movement and thereby prevent accidental loosening of the said wedging engagement.

15 Another object is to provide an improved one-piece anchor device provided with a jaw adapted to be driven into firm wedging engagement with one flange of the rail base, and provided with a portion which is torsioned during its application to a rail to effect a spring grip of the device on the rail base so as to hold the device in operative position thereon, the device being so formed as to be moved bodily, transversely 20 of the rail to its operative gripping position.

25 The invention has for further objects the novel arrangement, construction and combination of the various elements of the anchor device hereinafter described and claimed for carrying out the above stated objects, and such other objects as may appear from the following description.

In the drawing:

30 Fig. 1 is a plan view of the base portion of a railroad rail showing an anchor device constructed in accordance with my invention applied thereto, in its operative position.

35 Fig. 2 is an end elevation showing the anchor device in its applied position, and showing in dotted lines the position of the anchor before it is moved, and consequently subjected to torsional strain, to the position shown in full lines.

40 Fig. 3 is a side view of the anchor device showing the manner in which it is applied to the rail, the anchor being shown in the position which it assumes after it is twisted 45 to a position perpendicular to the rail base, but before it is driven transversely of the rail to its applied position.

45 Fig. 4 is a view similar to Fig. 3 showing

the anchor after it has been driven transversely of the rail to its rail-gripping position, and

55 Fig. 5 is a perspective of the improved anchor shown in the preceding figures.

Referring to the drawing, 10 designates 60 a railroad rail and 11 and 12 the base flanges of the rail supported on a cross tie 13.

The embodiment of my invention shown in the drawing consists preferably of a yoke 14, the upper portion of which is cut away to provide a rail base receiving recess 15, 65 and to provide jaws 16 and 17 which engage the inclined top faces of the base flanges of the rail at opposite sides of the rail. The recess is made larger than the width of the rail base, so as to permit the yoke to be hooked over the rail base at any desired 70 point, intermediate the ends of the rail, and then moved bodily transversely of the rail to its rail gripping position.

75 The jaw 16 is preferably bent at an angle to the body and preferably, though not necessarily, extends in a direction toward the cross tie. With an angularly disposed jaw of this character, the jaw, when the yoke is tilted in one direction about an axis transversely of the rail base, may be readily hooked over one flange of said base, whereupon the end of the jaw may then be forced down against the top surface of the base flange 11 of the rail by a tilting movement 80 of the yoke in the opposite direction.

85 The jaw 17 preferably extends in the plane of the body and the lower edge 19 thereof is inclined upwardly to correspond to the inclination of the top surface of the rail base. The portion of the recess 15 below the jaw 17 is of such size that the lower edge of the jaw 17 and the edge 20 of the yoke are forced 90 into firm wedging engagement with the top and bottom surfaces of the rail base respectively, when the anchor is driven to its applied position.

95 The anchor is made preferably of flat steel of any suitable degree of resiliency and the body portion is given a normal torsional set intermediate the jaws, so that it is necessary to twist the yoke in a direction tending to straighten out the torsional set, when moving the end 21 of the anchor to a position which will permit the jaw 17 to pass over the upper 100 edge of the rail base.

In application of the device to a rail, the yoke is tilted so as to permit the jaw 16 to be hooked over one flange of the rail base, for example, flange 11. The end 21 of the anchor may then be raised to a position opposite the flange 12 as shown in dotted lines in Fig. 2 of the drawing. A suitable wrench may then be applied to the end 21 of the anchor and the anchor twisted in a direction tending to straighten out the torsional set. This tensioning of the anchor forces the end of jaw 16 into a firm spring gripping engagement with the top face of base flange 11. When the end 21 is in a position substantially perpendicular to the bottom surface of the rail base, the anchor may be driven transversely of the rail from the position shown in Fig. 3 to the applied position shown in Fig. 4. In the latter position the jaw 17 and the lower edge of the recess 15 have a tight wedging engagement with the upper and lower surfaces of the rail base. When the anchor is driven from the position of Fig. 3 to the position of Fig. 4, the angular jaw 16 rides down the inclined surface of the base flange 11 and thereby partially relieves the tension of the yoke. The remaining tension of the yoke, however, will be sufficient to maintain a firm grip of jaw 16 on the rail and thereby prevent the anchor moving in a direction to loosen the grip of the jaw 17. Any movement of the anchor relative to the rail toward the left of Fig. 4 is resisted by reason of the fact that such movement tends to force the jaw 16 upon the inclined surface of the rail base so as to increase the torsion of the yoke.

The anchor, if desired, may be applied to the rail a short distance away from a cross tie and be then driven longitudinally of the rail so as to bear flatwise against the tie at right angles to the length of the rail. When the anchor is applied in this manner, it is preferably driven longitudinally of the rail so as to bear against the tie before the jaw 17 is driven home, this jaw being driven to its final position after the anchor is in engagement with the tie.

The wedging grip of the jaw 17 will ordinarily be sufficient to resist the normal creeping pressure of the rail. It will be observed, however, that in addition to the wedge grip of jaw 17 any pressure of the anchor against the tie tending to tilt the anchor, will increase the grip of the device by effecting a shackle grip of the jaw 17 and the body of the anchor upon the top and bottom surfaces of the rail. It will also be observed that when the anchor is applied to the rail with the angular jaw 16 extending toward the tie, any tendency of the anchor to tilt under the creeping pressure of the rail will increase the torsional strain of the anchor and thereby increase the grip of jaw 16 on the rail.

It will be seen from an inspection of the drawing that the jaw portion 16 of the anchor may be applied to either base flange of the rail. When it is applied to the edge of flange 12, the said jaw will extend longitudinally of the rail in a direction away from the tie. With such arrangement the tendency which the anchor has to return to the position from which it was twisted tends to effect a shackle grip of the jaw 17 and the body of the anchor upon the top and bottom surfaces of the rail base. It will also be observed that, with the anchor applied in this manner, any shackle grip of jaw 17, effected by reason of the resiliency of the metal, will be increased under the influence of the creeping pressure of the rail, and that such increased grip will be effected without increasing the spring grip of jaw 16.

While I have described my invention in connection with one specific embodiment, it will be obvious that the features of construction may be varied without departure from my invention. It will therefore be understood that I contemplate all such modified constructions as come within the scope of the appended claims.

I claim:

1. A rail anchor comprising a yoke formed at one end with a jaw adapted to be hooked over one flange of a rail base and at the other end with a jaw adapted to be moved into gripping engagement with the top and bottom of the base flange at the opposite side of the rail by movement of the anchor transversely of the rail; the said jaws being so disposed with relation to each other that it is necessary in applying the jaw last to engage the rail to subject the anchor to a torsional strain.

2. A rail anchor comprising a yoke formed at one end with a jaw adapted to be hooked over one flange of a rail base and at the other end with a jaw adapted to be engaged with the top and bottom surfaces of the other flange of the base near the edge thereof by movement of the anchor transversely of the rail; the first mentioned jaw being bent at an angle to the body of the anchor whereby it is necessary in applying the jaw last to engage the rail to subject the anchor to a torsional strain.

3. A rail anchor adapted to be driven transversely of a rail to its applied position comprising a yoke formed at one end with a jaw adapted to be hooked over one flange of a rail base and at the other end with a jaw disposed at an angle with relation to the first mentioned jaw whereby it is necessary to torsion the anchor to move said second mentioned jaw into a position to hook over the other rail base flange.

4. A rail anchor comprising a yoke provided with jaws adapted to be moved into operative gripping engagement with the

- base flanges of a rail at opposite sides of the rail by movement of the anchor transversely of the rail; the said jaws being so disposed with relation to each other that it is necessary to torsion the anchor during its application to a rail, said torsion being partially relieved by movement of the jaw last to engage the rail into normal gripping engagement.
- 5 5. A rail anchor comprising a yoke provided with jaws adapted to be moved into operative gripping engagement with the base flanges of a rail at opposite sides of the rail by movement of the anchor transversely of the rail; the said jaws being so disposed with relation to each other that it is necessary to torsion the anchor during its application to a rail, whereby one of said jaws is forced into spring gripping engagement with the rail base and whereby said spring grip is partially relieved by movement of the anchor to its normal operative position.
- 10 6. A rail anchor comprising a yoke provided with jaws adapted to be moved into operative gripping engagement with the base flange of a rail at opposite sides of the rail by movement of the anchor transversely of the rail; the said jaws being so disposed with relation to each other that it is necessary to torsion the anchor during its application to a rail and whereby maximum torsion is normally effected before the jaw last to engage the rail is moved into engagement with the rail base.
- 15 7. A rail anchor comprising a yoke formed at its ends with jaw portions for engaging the flanges of a rail base at opposite sides of the rail, one of said jaws being formed to provide clearance to permit the other jaw to be moved into preliminary position at the opposite side of the rail, the arrangement of said jaws being such that the yoke is torsioned and the first mentioned jaw forced into spring gripping engagement with the rail base by movement of the second mentioned jaw from said preliminary position to a substantially vertical position so that a forcible transverse movement of the anchor from the last mentioned position to its operative position partially relieves said torsion and causes the second mentioned jaw to have a strong wedging engagement with the rail.
- 20 8. A rail anchor comprising a yoke formed with jaws for engaging the flanges of a rail base at opposite sides of the rail, one of said jaws being bent at an angle to the body to provide clearance to permit the other jaw to clear the opposite edge of the rail base, the arrangement of said jaws being such that the movement of the last mentioned jaw into position to engage the rail base torsions the anchor so as to force the first mentioned jaw into spring gripping contact with the top of the rail base and whereby transverse
- 25 movement of the anchor forces the second mentioned jaw into wedging engagement with the rail base.
9. A rail anchor comprising a yoke formed with jaws for engaging the flanges of a rail base at opposite sides of the rail, one of said jaws being bent at an angle to the body to provide clearance to permit the other jaw to clear the opposite edge of the rail base, the body portion of the anchor being provided with a normal torsional set whereby movement of the last mentioned jaw into position to engage the rail base torsions the anchor so as to force the first mentioned jaw into spring gripping contact with the top of the rail base and the arrangement of said jaws being such whereby the transverse movement of the anchor forces the second mentioned jaw into wedging engagement with the rail base.
- 30 10. A rail anchor comprising a yoke formed with jaws for engaging the flanges of a rail base at opposite sides of the rail, one of said jaws being formed to provide clearance to permit the other jaw to clear the opposite edge of the rail base, the body portion of the anchor being provided with a normal torsional set whereby movement of the last mentioned jaw into position to engage the rail base torsions the anchor so as to force the first mentioned jaw into spring gripping contact with the top of the rail base and the arrangement of said jaws being such whereby transverse movement of the anchor forces the second mentioned jaw into wedging engagement with the rail base.
- 35 11. A rail anchor adapted to be driven transversely of the rail to its applied position comprising a yoke member formed at one end with a jaw portion for gripping the top and bottom surfaces of the rail base at opposite one side of the rail, and formed at the other end with an angularly disposed jaw adapted to bear with spring pressure upon the top surface of the rail base, said angular jaw being so disposed with relation to the first mentioned jaw as to effect a torsioning of the yoke when the anchor is applied to a rail.
- 40 12. A rail anchor adapted to be driven transversely of the rail to its applied position, comprising a yoke member formed with a jaw portion for gripping the top and bottom surfaces of the rail base at one side of the rail, and formed at the other end with a jaw adapted to bear with spring pressure upon the top surface of the rail base, one of said jaws being so disposed with relation to the other as to effect a torsioning of the yoke when the anchor is applied to a rail.
- 45 13. A rail anchor comprising a yoke provided with jaws adapted to be moved into gripping engagement with the base flanges

of a rail at opposite sides of the rail by movement of the yoke transversely of the rail; the said jaws being disposed with relation to each other, whereby the yoke is torsioned when in its applied position and whereby said torsion is increased by movement of the anchor in the direction to remove it from the rail.

14. A rail anchor comprising a yoke provided with means for bearing against the bottom surface of a rail base and provided with jaws for engaging the top surfaces of said base at opposite sides of the rail; the said jaws being disposed with relation to each other whereby the yoke is torsioned when in its applied position and whereby said torsion is increased by movement of the anchor in a direction to remove it from the rail.

15. A rail anchor adapted to be driven transversely of the rail to its applied position, comprising a yoke member formed with a jaw portion for gripping the top and bottom surfaces of the rail base at one side of the rail, and formed with a jaw adapted to bear with spring pressure upon the top surface of the rail base at the other side of the rail; the said jaws being disposed with relation to each other whereby the yoke member is torsioned when the anchor is in its applied position and whereby said torsion is increased by movement of the yoke in a direction to remove it from the rail.

16. A rail anchor adapted to be driven transversely of the rail to its applied position, comprising a yoke member formed with a jaw portion for gripping the top and bottom surfaces of the rail base at one side of the rail, and formed at the other end with a jaw adapted to bear with spring pressure upon the top surface of the rail base; said jaws being so disposed with relation to each other as to effect the torsioning of the yoke when the anchor is in its applied position whereby the torsional stress of the yoke is exerted through said first mentioned jaw to effect a shackle grip on the top and bottom surfaces of the rail base.

17. A rail anchor consisting of a bar of spring metal formed to provide rail base engaging jaws arranged so that after hooking one end of the anchor over one edge of a rail base the bar has to be twisted and moved transversely of the rail to engage the other edge of the rail base.

18. A rail anchor consisting of a bar of spring metal relatively thin with respect to the vertical dimension when applied to a rail formed to provide rail-base engaging jaws arranged so that after hooking one end of the anchor over one edge of the rail base the bar has to be twisted and moved transversely of the rail to engage the other edge of the rail base.

19. A rail anchor consisting of a bar of

spring metal relatively thin with respect to its vertical dimension when applied to a rail and adapted to lie substantially flatwise against one face of a cross tie and formed to provide rail base engaging jaws arranged so that after hooking one end of the anchor over one edge of a rail base the bar has to be twisted and moved transversely of the rail to engage the other edge of the rail base.

20. A rail anchor consisting of a bar of spring metal formed with a torsional set and formed with rail base engaging jaws arranged so that after hooking one end over one edge of a rail base the bar has to be twisted in a direction to straighten out said torsional set and moved transversely of the rail to engage the other edge of the rail base.

21. A rail anchor consisting of a bar of spring metal formed with jaw portions for engaging the upper and lower faces of a rail base and arranged so that after hooking one end of the anchor over one edge of the rail base the bar has to be twisted and moved transversely of the rail to engage the other edge of the rail base.

22. A rail anchor consisting of a bar of spring metal adapted to lie substantially flat-wise against one face of the cross tie and formed to provide rail base engaging jaws arranged so that after hooking one end of the anchor over one edge of a rail base the bar has to be twisted and moved transversely of the rail to engage the other edge of the rail base.

23. A rail anchor consisting of a bar of spring metal which is relatively thin with respect to its vertical dimensions when applied to a rail and formed with a torsional set and with rail-base engaging jaws arranged so that after hooking one end over one edge of the rail base the bar has to be twisted in a direction to straighten out said torsional set and moved transversely of the rail to engage the other edge of the rail base.

24. A rail anchor consisting of a bar of spring metal adapted to lie substantially flat-wise against one face of a cross tie and formed with a torsional set and with rail base engaging jaws arranged so that after hooking one end over one edge of the rail base the bar has to be twisted in a direction to straighten out said torsional set and moved transversely of the rail to engage the other edge of the rail base.

25. A rail anchor consisting of a bar of spring metal provided with jaw portions for engaging the upper and lower faces of a rail base and adapted to lie substantially flatwise against one face of the cross tie; the said jaws being arranged with relation to each other so that after hooking one end of the anchor over one edge of a rail base the bar has to be twisted and moved transversely of the rail to engage the other edge of the rail base.

26. A rail anchor consisting of a bar of spring metal relatively thin with respect to its vertical dimension when applied to a rail, provided with jaw portions for engaging the upper and lower surfaces of a rail base arranged so that after hooking one end of the anchor over one edge of a rail base, the bar has to be twisted and moved transversely of the rail to engage the other edge of the rail base.
27. A rail anchor adapted to be moved bodily relative to the rail to its rail gripping position comprising a yoke member, the body portion of which is formed with a substantially straight upper edge adapted to bear against the bottom surface of the rail base, and provided at opposite ends with jaw portions adapted to fit over opposite longitudinal edges of said rail base and bear upon the top surface of said base.
28. A rail anchor adapted to be moved bodily relative to the rail to its rail gripping position comprising a yoke member, the body portion of which is formed with a substantially straight upper edge adapted to bear against the bottom surface of a rail, and provided at opposite ends with long and short jaw portions adapted to fit over opposite longitudinal edges of said rail base, and bear against the top surface thereof.
29. A rail anchor adapted to be driven transversely of the rail to its applied position, comprising a yoke member, the body portion of which is formed with a substantially straight upper edge adapted to bear against the bottom surface of a rail base, and provided at opposite ends with jaws disposed at an angle with relation to each other and adapted to fit over opposite longitudinal edges of the rail base and bear against the top surfaces thereof.
30. A rail anchor comprising a yoke member recessed to provide at one end a relatively long jaw adapted to be hooked over one edge of a rail base, and at the other end with a relatively short jaw adapted to be forced into gripping engagement with said base by movement of the yoke transversely of the rail; the portion of the recess underlying said short jaw being of such width as to provide a wedging grip of said jaw upon the rail base.
31. A rail anchor comprising a yoke recessed to provide at one end a relatively long jaw adapted to be hooked over one edge of the rail base and at the other end with a relatively short jaw adapted to be forced into gripping engagement with said base by movement of the yoke transversely of the rail; the portions of said recess underlying said jaws being slightly less in width than the thickness of the rail base when the device is free of the rail, whereby it is necessary, in applying said jaws to their operative position, to subject said yoke to a torsional strain.
32. A rail anchor comprising a yoke provided with jaws adapted to be moved into operative gripping engagement with the base flange of the rail at opposite sides of the rail by movement of the anchor transversely of the rail; the portion of the yoke intermediate the said jaws being provided with a normal torsional set whereby it is necessary to torsion the said yoke during its application to a rail and whereby one of said jaws is forced into spring gripping engagement with the rail base and the other of said jaws being forced into a combined wedging and spring shackle grip, with the opposite edge of the rail.
